DESIGN FOR A TIRE COVER OR SIMILAR ARTICLE

George Albert Lyon, Asbury Park, N. J., assignor to Lyon Incorporated, Asbury Park, N. J., a corporation of Delaware

Application September 9, 1932. Serial No. 44,791

Term of patent 14 years

To all whom it may concern:

Be it known that I, GEORGE ALBERT LYON, a citizen of the United States, and residing in the city of Asbury Park, in the county of Monmouth and State of New Jersey, have invented a new, original, and ornamental Design for a Tire Cover or similar article, of which the following is the specification, reference being had to the accompanying drawing, forming a part thereof.

In the drawing:

Figure 1 is a view of a tire cover side face embodying the features of this invention.

Figure 2 is an enlarged cross-sectional view taken on the line 2-2 of Figure 1 in order to more clearly illustrate the outer contour of the cover, but it is to be understood that the present invention resides in the ornamental effect secured by the arrangement of the corrugations in a tire cover as illustrated in Figure 1.

I claim:

The ornamental design for a tire cover or similar article, as shown and described.

GEORGE ALBERT LYON.
